UNITED STATES PATENT OFFICE.

JOHN B. BOUDREAU, JR., OF WORCESTER, MASSACHUSETTS.

ROTARY ENGINE.

1,231,995.

Specification of Letters Patent.

Patented July 3, 1917.

Application filed June 19, 1916. Serial No. 104,394.

To all whom it may concern:

Be it known that I, JOHN B. BOUDREAU, Jr., a citizen of the United States, residing at Worcester, in the county of Worcester 5 and State of Massachusetts, have invented a new and useful Rotary Engine, of which the following is a specification.

The principal objects of this invention are to provide a rotary engine which, by mere 10 changes in design of the valve mechanism, can be built to be used either as a four cycle gas engine or as a steam engine; to provide a construction which when used as a steam engine will have an automatic cut-off to permit 15 the steam to expand in the same manner substantially as in the reciprocating engine operating with or without a condenser; to provide a simple construction by which the speed of the rotors is made to increase and 20 decrease during each complete rotation and in which one cylinder is always under pressure because one piston is approximately 90 degrees ahead of the other throughout the revolution; to provide for reversing the 25 direction of rotation easily; to provide for a wide variation in speed up to the speed of steam turbines; to provide mechanism of such a character that steam will be admitted 30 through the same port for both of the strokes and exhausted through a single port for both of the strokes, the engine being designed to provide two strokes for each complete revolution; to provide a construction 35 which will not require much foundation or stationary work, which can be directly connected with another rotary machine of the 40 same type without valves so as to be capable of being used as an air compressor, to produce a complete air compressing system, thus permitting of the equipping of each room or 45 department with a small rotary engine of this type connected with the compressed air in the power house, to form an installation similar in results to the ordinary electrical system, but having the following advantages; these small engines are much cheaper 50 than electrical motors as there is no fire risk from electrical lines, great speed variation is obtainable, no skilled attendants are required, no extra gears are required to operate individual machinery, and no care is required as to cleanliness or dryness of the locality where power is needed.

It will be understood, of course, that in 55 addition to the above advantages this invention secures the usual advantages of rotary

engines, namely the location of the parts in such a manner that a reduction in pressure at points in the stroke owing to the angularity of the connecting rod is avoided, the 60 heavy frame is not required, and the great space occupied per horse power is greatly reduced; to provide two explosions for each complete revolution; to provide means whereby the pressure is active throughout 65 two-thirds of the length of each stroke or one revolution and a half for each revolution of the engine; and to provide a construction which with the same positive area and displacement will be many times as 70 powerful as a reciprocating gas engine of the best type known at the present time.

Reference is to be had to the accompanying drawings, in which—

Fig. 1 is a front elevation of an internal 75 combustion engine constructed in accordance with this invention, the valve mechanism being omitted.

Fig. 2 is an end elevation looking in the direction of the arrow 2 in Fig. 1;

Fig. 3 is a sectional view on the line 3—3 of Fig. 2, showing the parts in another position;

Fig. 4 is a sectional view through the exhaust chambers on the line 4—4 of Fig. 2, 85 showing the parts in a third position;

Fig. 5 is a sectional view through the admission chambers on the line 5—5 of Fig. 2, showing the reversing connections for the admission;

Fig. 6 is a front view like Fig. 1, but with the gears removed and their shafts in section, and showing the exhaust valve mechanism, and the reversing means therefor;

Figs. 7, 8, 9 and 10 are diagrammatic views, showing different positions of the rotors; Fig. 9 also indicating the exhaust valve mechanism in one of its positions;

Fig. 11 is a front view of a rotary steam 100 engine constructed in accordance with this invention, the gearing being omitted;

Fig. 12 is a sectional view of the same through the cylinders, and

Figs. 13 and 14 are sectional views of the 105 in-take and exhaust respectively.

Referring first to the first ten figures, it will be seen that the invention is illustrated in these figures in a form involving a frame 10 having two cylinders each complete in 110 itself. It is to be understood that this is chosen as an example for illustration, and

that the principles of the invention can be carried out with one or any other convenient number of cylinders. This frame is provided with bearings for the main shaft 5 11 which carries the fly wheel 12, and is provided also with five other principal shafts 13, 14, 140, 14^a and 140^a. The shafts 14 and 14^a are in alinement and the same is true of 140 and 140^a. They are independently rotatable. The shaft 13 is connected with the shaft 11 by a pair of spur gears 15. As will appear later the shaft 13 serves as a valve cam shaft. To it are fixed at its opposite ends two elliptical gears 16 and 16^a. These gears are set on the shaft exactly oppositely to each other. The gear 16 meshes with two elliptical gears 17 and 18 on the shafts 14 and 140 respectively, and on the shafts 14^a and 140^a are two elliptical gears 17^a and 18^a both meshing with the gear 16^a.

It will be seen that the gears 16, 17 and 18 are located in the same plane, and the gears 16^a, 17^a, and 18^a are also located in the 25 same plane, on the other side of the machine in the form shown in the drawings.

The object of this type of gearing is to provide for rotating the two shafts of a pair as 14 and 14^a differently, and also to rotate 30 each of them at different speeds during each revolution, so that each shaft increases and decreases in speed.

Each of these gears is fixed to its shaft at one of its foci. The gears 16 and 16^a are 35 intended to rotate at constant speed so that the shafts 13 and 11 may rotate without speed variations. In order to do this the shaft 14, for example, must have a variation in speed during each rotation. For while 40 the gear 16 meshes at a point near its shaft 13 with teeth of the gear 17 at a distance from the shaft 14, the shaft 14 must rotate faster than the shaft 13 and vice versa.

These elliptical gears constitute an important feature of this invention and attention is directed to the manner in which they are arranged. The two gears 16 and 16^a are fixed on the same shaft 13 and extend in 45 exactly opposite directions from it. These 50 gears as well as the others are fixed to their respective shafts at one of their foci. The several gears are so arranged that when any gear extends from its shaft toward one of the other shafts the gear with which it 55 meshes will extend in a different direction so that its teeth that are nearer this shaft will still mesh with the teeth of the first named gear. From this it results that as the gear 16, for example, rotates, its teeth 60 nearest the shaft 13 will be meshing with the teeth farthest from the shaft of the gear 17, while its opposite teeth are meshing with the, so to speak, shortest teeth of the gear 18. Therefore, the shaft 14 at this 65 time will be rotating slowly while the shaft

140 will be rotating rapidly. Furthermore while the gear 17 is in this position and its shaft 14 is rotating slowly the gear 17^a on the other side has passed beyond this point so that it just now is rotating at about its 70 average speed and will soon come into a position in which it will rotate at its maximum speed. Speed variations are indicated on Figs. 7, 8, 9 and 10 by the use of barbless arrows to indicate slow speed and arrows with several barbs to indicate high speed.

The free foci of the gears are connected by links 19. I find that these links operate exactly with the gears and tend to help 80 turn them when located nearly in their directions of motion. In fact they alone, in combination with straight arms on the shafts in place of the gears, the links being pivoted to them as they are to the gears, would operate the shafts in the same way except that there would be no positive means for helping the shafts over their dead centers. The gears accomplish this.

Referring more particularly to the diagrammatic views, Figs. 7, 8 and 9 it is to be observed that on the shaft 14 is a rotor 20 while on the shaft 14^a is a rotor 20^a. The other cylinder can be ignored for the present, but on the shaft 140 is a rotor 21 while on the shaft 140^a is a rotor 21^a. Referring now to the left-hand cylinder these two rotors 20 and 20^a are fixed to their respective shafts, and of course rotate absolutely with them. Each one of them is of an L-shape 10 cross section so that each rotor fills all the space between the hub of the opposite rotor and the cylinder wall. Each rotor therefore fills the entire space across the cylinder and serves as a piston at times but at other times as the end of the cylinder or as an abutment.

An admission port 22 and an exhaust port 23 are shown in these figures as slightly offset from each other, but this is done merely to distinguish them, as I prefer to have them 11 directly opposite each other as shown in the other figures, each one opening into one of the flat walls of the cylinder. They are, of course, controlled by a valve, but for a description of these diagrammatic figures that fact may be ignored.

Starting with the position shown in Figs. 4 and 8 the parts are rotating in the direction of the arrows and gas is admitted through the port 22 into the space in front of the rotor 20 of the left-hand cylinder. At this time the gear 17 which is fixed with respect to this rotor 20 is in a position in which the uniformly rotating gear 16 rotates it at a rapid speed, that is, the gear 16 applies a long leverage to the teeth on the gear 17 nearest the focus at which it is fixed to its shaft. Therefore this rotor is moving at a high rate of speed, this being indicated by an arrow with a plurality of barbs.

At the same time the other rotor is rotating with its gear 17^a in what may be considered the opposite condition, that is, the teeth near the focus of the gear 16^a at which it is fixed to its shaft are about to mesh with those teeth on the gear 17^a that are at a greater distance from its shaft. Therefore the rotor 20^a is slowing down as indicated by the barbless arrow.

10 The gas is introduced through port 22 into the space in front of the rotor 20 and as soon as that rotor covers the port 22 compression will commence to take place and will continue until the parts reach the position shown in Figs. 3 and 9, at which the rotor 20^a has advanced beyond the igniter 24 and the latter acts to explode the gases. The two rotors at this point are traveling at about the same speed which is an intermediate speed, but immediately the rotor 20^a is rendered capable of moving at a rapid rate by the fact that its gear 17^a comes around so that the teeth at a short distance from its shaft mesh with the teeth of the gear 16^a at a long distance from the shaft 13. This rapid motion of the rotor 20^a which is now the advance rotor is necessary in order to give a chance for the expansion stroke to do the necessary work. The beginning of the expansion stroke in the left hand cylinder is shown in Fig. 10.

This rotor 20^a then continues to rotate rapidly until it gets back almost to the position shown in Figs. 1 and 7. That is, to the position in which it uncovers the exhaust port 23 behind it. Then the products of combustion in the cylinder behind the rotor 20^a are exhausted and it will be noted that from this point on the cycle takes place in front of the rotor 20^a instead of in front of the rotor 20. Fig. 7 shows the parts in position in which the rotor 20 has commenced to travel rapidly on its expansion stroke. It will be seen therefore, that for one complete rotation of the two shafts 14 and 14^a there will be two complete cycles of the engine, that is, each rotor will go through the cycles of admission, compression, expansion and exhaust of gases in front of it, each rotor acting first as an abutment of the cylinder and then as a piston.

It will be seen also that when one rotor is acting as an abutment, as 20^a in Fig. 7, the piston rotor 20 is exerting force on it to operate it through the gearing, and that force is multiplied twice. In this position the piston rotor 20 positively drives the shaft 14 and gear 17 which are fixed to it. The gear 17 applies a leverage through its long arm to the short arm of the gear 16, so to speak, as shown in Fig. 1. Then the shaft 13 is acted on by a multiplied force. At the same time this shaft through the long arm of the gear 16^a and short arm of gear 17^a is acting on the abutment 20^a which thus

moves slowly. This double multiplication of power is important because the pressure between the rotors acts on both of them to drive them in opposite directions. The abutment acts more nearly like a fixed wall than in those cases lacking this double multiplication.

With this explanation of the general operation of the engine I shall now proceed to describe the valve mechanism: As the exhaust valve mechanism is simpler I shall describe that first. At the upper part of the frame of the machine is a shaft 25. On this are pivotally mounted the two exhaust valve levers 26 and 26^a. Each of these is adapted to press on a spring-pressed valve rod as 27 and 27^a. The rod 27 operates an exhaust valve 28 which is provided with a spring for pressing it upwardly into closed position. This valve controls an outlet port 85 from a chamber 29. This chamber is elongated and located on the outside of one of the flat walls of the cylinder. Instead of a single exhaust port 23 as indicated in the description of the diagrammatic figures this 90 chamber is provided with two exhaust ports 23 and 23^a and with two valves 30 and 30^a for these ports. In the description of the diagrammatic figures it has been considered that the valve 30^a was closed and the valve 95 30 open. This valve 30 has a longitudinal passage therethrough from the port 23 on the inside of the cylinder into the chamber 29, and consequently the uncovering of the port 23 by the rotor will admit the products 100 of combustion from the chamber 29 at all times while this condition exists, but the real exhaust is controlled by the valve 28. These parts of course, are duplicated in the other cylinder.

The purpose of having two of these exhaust ports is to provide a convenient method of reversal. When the parts are set as has been described above the engine will rotate in its normal forward direction. 110 When the valve 30 is closed and the valve 30^a open the engine will rotate in the opposite direction provided, of course the admission valves are correspondingly manipulated. For the purpose of turning these valves they 115 are provided with stems 31 and 31^a. These stems are connected with the corresponding stems from the other cylinder by means of a rod 32. One of the valve stems is provided with an offset portion 33 and connected by a 120 link 34 with an arm 35 on the shaft 25. This shaft also is provided with another arm 36 on the other end and I have shown one of these arms as extending beyond the shaft in the opposite direction with a handle 37 125 by which the shaft can be turned and both of the arms 35 and 36 lowered. It will be obvious that the turning of the shaft through a part of a revolution will tip the link 32 from the full to the dotted line po- 130

sition in Fig. 6 and thus provide for reversal on the exhaust side.

On the other side a link 38 is connected with the arm 36 and with a projection 40 on one of the admission valve arms 41 to shift them in a similar manner. These admission valves as 42 and 42^a are arranged like the exhaust valves to close or open the ports 22 and 22^a and are so set that only one of these ports may be opened at the same time. These ports open into a chamber 43 which is supplied with fuel through a passage 44 which is controlled by a valve 45 on a spring-pressed stem 46. The spring normally keeps this valve closed and it is opened by pressure on the stem by an arm 47 pivoted on the shaft 25. These parts of course, are duplicated for the other cylinder, the other arm being designated 47^a. The arms 37 and 36 are provided with depending links 48 and 48^a which are adapted to be operated by cams 49 and 49^a respectively on the shaft 13. Likewise the arms 26 and 26^a are designed to be operated by cams 50 and 50^a also on this shaft. The operation of these cams simply swings the arms 26 and 26^a outwardly so as to depress the respective arms of these bell-crank which press on the valve rods 27 and 27^a. In the case of the admission valves, however, the action is somewhat different, although similar. When the engine is to be reversed the time of admission has to be changed although the time of exhaust does not in the present design. This makes the admission valve mechanism slightly more complicated than that of the exhaust. Therefore each admission valve arm as 47 is provided with a downwardly extending projection as 53, each one of which is connected by a link as 54 or 54^a with the opposite depending link. That is, the arm 53 is connected by the link 54 with the depending link 48, while the link 54^a is connected with the depending link 48^a. The cams force outwardly the bottoms of the links 48 and 48^a and transmit that motion through the links 54 and 54^a to the bell-crank 53—47 and 53^a—47^a. The effect of turning the shaft 25 on which these levers are loosely mounted is not only to reverse the engine by changing the valves 42 and 42^a as well as the exhaust valves 30 and 30^a, but it also changes the time of admission by raising one of the links 48 and 48^a and lowering the other. While these links are still operated by the same cams they are operated at a different time because the admission has to be advanced or retarded when it is brought in at the other port for reversal.

It will be seen, therefore, that by this construction an internal combustion engine is provided of the four-cycle type in which two explosions are secured for each complete revolution of the shaft, in which the cycles are carried out in substantially the same way as

in an ordinary reciprocating gas engine, but with all the advantages heretofore claimed for various types of rotary engines; in which the reversal is accomplished in a very simple manner, and by which the other advantages above mentioned can be secured.

Substantially the same construction can be used for a steam engine, and on the last sheet of drawings I have shown a steam engine constructed in accordance with this invention. However, I have not repeated in those figures the gearing shown on the first sheet as it is exactly the same. In this case the shafts 11, 13, 14, 14^a, 140 and 140^a and the rotors 20, 20^a, 21 and 21^a are used as in the other case, but in this case it is the shaft 11 that is the eccentric shaft for controlling the valve motion. Each cylinder is provided with two admission ports 60 and 61 and with an admission valve 62 which can be turned to three positions. In the position shown at the left in Fig. 12 it delivers steam between the two rotors 20 and 20^a so as to force the former forward with a high speed while the rotor 20^a is moving in the same direction at a low speed. This provides for the power stroke. While running in this direction the left-hand exhaust port 63 of this cylinder is closed by its valve 64 while the right hand exhaust port 65 is opened by its valve 66 being located in proper position for discharging the exhaust steam through it. It is to be understood that in this case the valves 64 and 66 are simply moved by a link 67 into proper position to close one valve and open the other and that the discharge of the exhaust steam is controlled by the rotor itself. When the rotor 20 passes over the port 65 steam is free to exhaust without further movement of the valve 66. The right hand side in Fig. 12 shows the admission valve 62 closed.

The parts can be moved to reversing position by shifting the link 67 over into the dotted line position in Fig. 11, thus closing the valve 66 and opening the valve 64, and at the same time shifting the admission valve motion from the full to the dotted line position. This admission valve motion comprises two eccentrics 70 on the shaft 11 which by means of their rods operate two pivoted members 71, one for each of the cylinders. Each member 71 is connected by link 72 to an arm 73 fixed to the stem of the valve 62. Upon reversal by moving a lever 74 and its shaft 25 to the dotted line position the two arms 72 will be shifted so that the valve 62 when open will deliver the steam through the port 60 instead of the port 61. This provides for reversal. Of course in this case the port 63 is open and the port 65 closed.

Many of the advantages set forth in connection with the gas engine are also present in this one as will be understood. The gear-

ing is unchanged, and the design of the two engines is similar throughout, the valve motion being the principal part in which changes have to be made. It will be under-

5 stood further that the course of the supply and exhaust can be arranged for a steam engine similarly to that shown for a gas engine, but I prefer to arrange them as shown in the drawings.

10 Although I have illustrated and described only two forms of the invention I am aware of the fact that many modifications can be made therein by any person skilled in the art without departing from the scope of the 15 invention as expressed in the claims. Therefore, I do not wish to be limited to all the details of construction shown in either form, but what I do claim is:—

1. In a rotary engine, the combination of 20 a cylinder, two rotors therein adapted to rotate independently about the axis of the cylinder, a member fixed with respect to each rotor to rotate therewith and projecting from the axis of rotation, a shaft parallel 25 with the axis of the cylinder, two members projecting in opposite directions from said shaft, all of said members having intermeshing gear teeth, and two links each connecting one of the last named members with 30 one of the first named members.

2. In a rotary engine, the combination of 35 a cylinder, two rotors therein adapted to rotate independently about the axis of the cylinder, an elliptical gear fixed with respect to each rotor to rotate therewith and projecting from the axis of rotation, a shaft parallel with the axis of the cylinder, two elliptical gears projecting from said parallel 40 shaft, and two links each pivotally connecting one of the last named elliptical gears directly with one of the first named elliptical gears.

3. In a rotary engine, the combination of 45 a cylinder, two rotors therein adapted to rotate independently about the axis of the cylinder, an elliptical gear fixed with respect to each rotor to rotate therewith and projecting from the axis of rotation, a shaft parallel with the axis of the cylinder, two elliptical 50 gears projecting in opposite directions from said shaft, each of said elliptical gears being fixed to its shaft at one of its foci, and two links each connecting one of the last named elliptical gears with one of the first 55 named elliptical gears at their other foci.

4. In a rotary engine, the combination of 60 two cylinders, two rotors in each one adapted to rotate independently about the axis of its cylinder, four shafts, two in line with each other, to each of which one of said rotors is fixed, an elliptical gear fixed to each shaft at one of its foci, a shaft parallel with said shafts, and two elliptical gears 65 fixed at their foci thereto and projecting in opposite directions therefrom, one meshing

with each pair of of the first named elliptical gears, whereby motion is transmitted alternately from each of said shafts to the single shaft.

5. In a rotary engine, the combination of 70 a cylinder, a rotor located therein and adapted to rotate about the axis of the cylinder, a shaft at the axis of the cylinder to which said rotor is fixed, an elliptical gear on the shaft, a shaft for receiving power, an elliptical gear thereon meshing with the first named elliptical gear throughout the rotation thereof, for transmitting a variable motion of rotation from the rotor to the shaft at a constant speed, said cylinder having 75 open admission and exhaust ports through its flat sides adapted to be opened and closed by the rotor, and valves independent of said ports for controlling the admission and exhaust independently of the position 80 of the rotor.

6. In an internal combustion rotary engine, the combination of a cylinder, two rotors therein adapted to rotate independently about the axis of the cylinder, two 90 shafts in line with each other to each of which one of said rotors is fixed, a transmission shaft, means whereby motion is transmitted from each of said shafts to the transmission shaft, an exhaust chamber and an 95 admission chamber, an exhaust port through one flat side of the cylinder communicating constantly with the exhaust chamber, an admission port through the other flat side of the cylinder communicating constantly with 100 the admission chamber, an admission valve for admitting combustible material to the admission chamber, and an exhaust valve for opening the exhaust chamber.

7. In a reversible internal combustion rotary engine, the combination of a cylinder, two shafts therein independently rotatable about the axis thereof, a rotor fixed to each shaft and located in the cylinder, each rotor being adapted to fill the entire space across 105 the cylinder, a shaft parallel with said shafts, means for transmitting the varying rotation of the rotors to the last named shaft at a constant speed, an admission and an exhaust chamber, two exhaust ports and two admission ports communicating with the exhaust and admission chambers respectively, valves for all of said ports, said ports being located in such position that when one exhaust and admission port are open the rotors will rotate in one direction, and when the other exhaust and admission port are open the rotors will rotate in the other direction, and means for closing one of the admission 110 and one of the exhaust ports and opening 115 the other of each to determine the direction of rotation of the engine.

8. In a reversible rotary engine, the combination of a cylinder, two shafts independently rotatable, a rotor fixed to each shaft 120

and located in the cylinder, each rotor being adapted to fill the entire space across the cylinder, a shaft parallel with said shafts, means for transmitting the varying rotation 5 of the rotors to the last named shaft as a rotation of constant speed, an admission and an exhaust chamber outside the cylinder, said cylinder having two exhaust ports and two admission ports through its walls, the 10 exhaust ports communicating with the exhaust chamber, and the admission ports with the admission chamber, valves for all of said ports, said ports being located in such position that when one exhaust and 15 admission port are open the rotors will rotate in one direction, and when the other exhaust and admission port are open the rotors will rotate in the other direction, means for closing one of the admission and 20 one of the exhaust ports and opening the other of each to determine the direction of rotation of the engine, an inlet to the admission chamber, an outlet from the exhaust chamber, and inlet and outlet valves 25 for controlling said inlet and outlet for the purpose of timing the admission and exhaust.

9. In a rotary engine, the combination of a cylinder, two shafts, a rotor fixed to each 30 shaft and located in the cylinder, each rotor being adapted to fill the entire space across the cylinder, a shaft parallel with said shafts, means for transmitting the varying rotation of the rotors to the last named shaft 35 as a rotation of constant speed, an admission and an exhaust chamber outside the cylinder, said cylinder having two exhaust ports and two admission ports through its walls, the exhaust ports communicating 40 with the exhaust chamber, and the admission ports with the admission chamber, valves for all of said ports, said ports being located in such position that when one exhaust and admission port are open the rotors 45 will rotate in one direction, and when the other exhaust and admission ports are open the rotors will rotate in the other direction, means for closing one of the admission and 50 one of the exhaust ports and opening the other of each to determine the direction of rotation of the engine, an inlet to the admission chamber, an outlet from the exhaust chamber, admission and exhaust 55 valves for controlling said inlet and outlet for the purpose of timing the admission and exhaust, and means for automatically operating said valves as the rotors rotate.

10. In a rotary engine, the combination of a cylinder, two shafts independently rotatable about the axis thereof, a rotor fixed to each shaft and located in the cylinder, each rotor being adapted to fill the entire space across the cylinder, a shaft parallel with said shafts, means for transmitting the 65 varying rotation of the rotors to the last

named shaft as a rotation of constant speed, an admission and an exhaust chamber, two exhaust ports and two admission ports communicating with the exhaust chamber and the admission chamber respectively, valves 70 for all of said ports, said ports being located in such position that when one exhaust and admission port are open the rotors will rotate in one direction, and when the other exhaust and admission port are open 75 the rotors will rotate in the other direction, means for closing one of the admission and one of the exhaust ports and opening the other of each to determine the direction of rotation of the engine, an inlet to the admission chamber, an outlet from the exhaust chamber, admission and exhaust 80 valves for controlling said inlet and outlet for the purpose of timing the admission and exhaust, means for automatically operating said valves as the rotors rotate, and means whereby when the first named valves are set to change the direction of rotation 85 the timing of the admission valve will be changed also.

11. In a rotary engine, the combination of a cylinder, two shafts, a rotor fixed to each shaft and located in the cylinder, each rotor being adapted to fill the entire space across the cylinder, a shaft parallel with 90 said shafts, means for transmitting the varying rotation of the rotors to the last named shaft as a rotation of constant speed, an admission and an exhaust chamber outside the cylinder, said cylinder having two exhaust ports and two admission ports through its walls, the exhaust ports communicating with the exhaust chamber, and the admission ports with the admission chamber, valves for all of said ports, said ports being located in such position that when one exhaust and admission port are open the rotors will rotate in one direction, and when the other exhaust and admission ports are open the rotors will rotate in the other direction, means for closing one of the admission and 100 one of the exhaust ports and opening the other of each to determine the direction of rotation of the engine, a reciprocal link connected with the two exhaust valves of the exhaust chamber, a reciprocal link connected with the two valves of the admission chamber so as to open one of the valves and close the other in each extreme position of the link, and means for 105 simultaneously moving said links to close the admission and exhaust valves in line with each other at one end of each chamber and open the others.

12. In a rotary engine, the combination of 115 a cylinder, two rotors arranged therein and independently rotatable about the axis thereof, an admission and an exhaust chamber, said cylinder having two exhaust ports and two admission ports through its walls, 120

- the exhaust ports communicating with the exhaust chamber, and the admission ports with the admission chamber, valves for all of said ports, said ports being located in 5 such position that when one exhaust and admission port are open the rotors will rotate in one direction, and when the other exhaust and admission port are open the rotors will rotate in the other direction, means for closing 10 one of the admission and one of the exhaust ports and opening the other of each to determine the direction of rotation of the engine, a reciprocable link connected with the two valves of the exhaust chamber, a 15 reciprocable link connected with the two valves of the admission chamber so as to open one of the valves and close the other in each extreme position of the link, means for simultaneously moving said links to 20 close the admission and exhaust valves at one end of each chamber and open the others, an admission valve for admitting fuel to the admission chamber, a cam for operating said valve, and means whereby 25 when the first named valves are turned the connection between said cam and admission valve will be changed to advance or retard the admission.
13. In a rotary engine, the combination of 30 a casing having a cylinder, rotors therein, said casing having a port communicating with the interior thereof, a valve for closing said port, means for normally holding the valve closed, a cam, a bell-crank in position 35 to be operated by said cam and arranged to open said valve periodically, a link connected with said bell-crank and movable to and fro for changing the time at which the cam operates, and means connected with 40 said link for operating the bell-crank.
14. In a rotary internal combustion engine, the combination of two cylinders arranged side by side with parallel axes, two rotors in each cylinder rotatable independently of each other, connections between the 45 four rotors for causing them to rotate at varying speeds during a revolution, a cam shaft, admission and exhaust cams on said shaft for each cylinder, an admission valve 50 for each cylinder, an exhaust valve for each

cylinder, means operated by the respective cams for periodically opening said valves, and means whereby the opening of the admission valves can be advanced or retarded.

15. In a rotary internal combustion engine, the combination of two cylinders arranged side by side with parallel axes, two rotors in each cylinder rotatable independently of each other, connections between the four rotors for causing them to rotate at 55 varying speeds during a revolution, a cam shaft, admission and exhaust cams on said shaft for each cylinder, an admission valve for each cylinder, an exhaust valve for each cylinder, an oscillatable shaft, two admission 60 valve-controlling levers loosely mounted on said shaft, a lever fixed on said shaft for turning it, a pair of links depending from said lever into position to engage the admission valve cams, and means connected with 65 each link for operating its admission valve lever, whereby when said shaft is turned the depending links will be raised or lowered, and the time at which the cams operate them changed. 70

16. In a rotary internal combustion engine, the combination of two cylinders arranged side by side with parallel axes, two rotors in each cylinder rotatable independently of each other, connections between the 75 four rotors for causing them to rotate at varying speeds during a revolution, a cam shaft, admission and exhaust cams on said shaft for each cylinder, an admission valve for each cylinder, an exhaust valve for each 80 cylinder, means operated by the respective cams for periodically opening said valves, an admission and an exhaust chamber communicating with each cylinder between the cylinder and said admission and exhaust 85 valves respectively, and means whereby the point of admission from the admission chamber to each cylinder and the point of exhaust into the exhaust chamber from the cylinder can be changed for reversal of the 90 engine.

In testimony whereof I have hereunto affixed my signature.

JOHN B. BOUDREAU, JR.
